(57) **CLAIM**

The ornamental design for a wire dispenser apparatus, as shown and described.

DESCRIPTION

This application is related to U.S. application Ser. No. 14/599,540, filed on Jan. 18, 2015, now U.S. Pat. No. 9,926,167 B1.

FIG. 1 is a top left, front perspective view of a wire dispenser apparatus showing my new design;

FIG. 2 is a left side view thereof;

FIG. 3 is a front elevational view thereof;

FIG. 4 is a right side view thereof;

FIG. 5 is a rear elevational view of thereof;

FIG. 6 is a top plan view thereof; and,

FIG. 7 is a bottom plan view thereof.

1 Claim, 7 Drawing Sheets
